a corporation of New Jersey

Application December 7, 1948, Serial No. 63,957

3 Claims. (Cl. 62—1)

1

The invention relates to containers for gas under pressure and from which the gas is to be dispensed or delivered at reduced pressure by passage through a constricted orifice. In cigar lighters fueled by gases such as butane or propane for example, it is possible to charge the fuel in liquid form into a container which is thereupon sealed, whereupon the liquid changes in phase to the gaseous form and provides a relatively large supply of gaseous fuel under pressure substantially higher than is desired to be used at the burner of the lighter. The present invention aims primarily to provide a pressure reducing diaphragm structure appropriate for use in connection with containers of the above character, and which has special advantages in respect to simplicity of construction and the facility with which the diaphragm member may be anchored in operative position immediately after the fuel charging operation to minimize the loss of fuel through the charging opening, and removed from such position preparatory to recharging with fuel as hereinafter described in greater detail. Further objects and advantages of the invention will be in part obvious and in part specifically referred to in the description hereinafter contained which, taken in conjunction with the accompanying drawings, discloses a preferred form of diaphragm structure constructed to operate in accordance with the invention; the disclosure however should be considered as merely illustrative of the invention in its broader aspects. In the drawings:

Fig. 1 is a central vertical section taken through a fuel container having a pressure reducing diaphragm structure constructed to operate in accordance with the invention.

Figs. 2 and 3 are enlarged detail sections showing the diaphragm member respectively before and after the operation of anchoring it in place in the container.

Fig. 4 is an enlarged detail section including a type of tool or fixture which may be used to assist in the fuel charging operation and in anchoring the diaphragm member in operative position.

Fig. 5 is an enlarged detail section including a type of tool which may be used in removing the diaphragm member from operating position.

The invention is disclosed as applied to a container 1 which may be assumed to be of form appropriate for use as the fuel receptacle of a cigar lighter, and which contains a filling 2 of absorbent material such as cotton. The container 1 is shown as provided with an internal

boss 3 which has a passageway 4 extending therethrough. When the container 1 is to be charged with fuel, the parts which appear in the Fig. 1 above the passageway 4 will be removed, and fuel such as butane or propane in liquid form will be introduced into the container through passageway 4, after which the above mentioned parts will be assembled to seal the container, whereupon the fuel will convert into gaseous form to afford a supply of gaseous fuel under substantial pressure, which may easily be sufficient to afford several years of normal use of the lighter before re-charging with fuel is necessary.

15 To minimize initial loss of fuel through passageway 4, and also reduce the gaseous pressure at which the fuel is supplied to the burner of the lighter, a pressure reducing diaphragm member as hereinafter more fully described, is interposed between passageway 4 and the parts which appear above this passageway in Fig. 1, and is inserted into operative position immediately after the fuel has been charged in. This pressure reducing diaphragm member as shown more in detail in Fig. 2, comprises a thin deformable disk of resilient metal having a small pressure reducing aperture 5 extending through the central portion 6 of the diaphragm, the peripheral or rim portion 7 of the diaphragm being received in an annular seat in boss 3, said seat having a bottom wall 8 against which the rim portion 7 of the diaphragm rests, and an annular wall 9 which encloses the diaphragm.

As indicated in Fig. 2 the natural or initial shape of the diaphragm member is somewhat concavo-convex, such that the central portion 6 of the diaphragm is displaced to one side with respect to the general plane of the rim portion of the diaphragm, although it is not necessary that the rim portion shall partake of this curvature. Under the above conditions, that is when the diaphragm is initially placed in its seat, its over-all diameter as shown in Fig. 2, is such that it fits fairly snugly into the seat, the parts which appear above the diaphragm in Fig. 1 being detached at this stage. Then the central portion of the diaphragm is deformed by transverse pressure as indicated in Fig. 3 to displace this central portion toward the plane of the rim 40 of the diaphragm, thus expanding the rim portion of the diaphragm radially outward until it locks firmly against the enclosing wall 9 and seals the joints between the two members. Preferably the diaphragm is provided with a sharpened peripheral edge 10 as indicated in Figs. 2, 3,

and 5, to cause it to bite into the wall 9 when the diaphragm is deformed as above described, and preferably as indicated in Fig. 3 the above deforming operation is carried far enough to slightly reverse the initial curvature of the central portion of the diaphragm lest the latter snap back to its initial curvature when the pressure is released.

In Fig. 4 I have shown a type of tool which may be conveniently used in charging liquid fuel into the container 1 and for inserting the above described pressure reducing diaphragm immediately after the fuel charging operation is completed. In the form shown this tool is provided with a threaded tube 11 which is screwed into the boss 3, and provided with a conduit 12 through which the liquid fuel is conducted. A screw 13 is threadedly received within the collar 11, and at its lower end this screw is provided with a pilot pin 14 which fits frictionally within the aperture 5 of a pressure reducing diaphragm such as is above described, the diaphragm being then in the shape shown in Fig. 2. During the fuel charging operation this screw 13 and the pressure reducing diaphragm carried thereby, will remain in the upper position shown in Fig. 4, but immediately after the fuel charging operation is completed, the screw 13 will be turned to move downwardly until the rim portion 7 of the diaphragm seats against the wall 8 of boss 3. The lower face of the screw 13 is shown as provided with an annular sharp ridge 15 which engages the rim portion 7 of the pressure reducing diaphragm, and the portion 16 of the bottom face of the screw which is enclosed by this ridge 15 is in the form of a cone with its conical side wall making an angle of about 5° with the horizontal. Thus as the diaphragm is forced against the wall 8 by screw 13 the diaphragm assumes the shape shown in Fig. 3, after which the above described tool will be removed, leaving the diaphragm firmly seated and sealed in position so that fuel can escape from the container only through the aperture 5 of the diaphragm which is exceedingly small in size.

Then after the tool shown in Fig. 4 has been removed, an appropriate valve mechanism is inserted to shut off the flow of fuel through the orifice 5 except when desired. Fig. 1 shows merely by way of example, a valve mechanism which may be so used. I prefer to place immediately above the diaphragm, a disk 17 of soft metal such as lead, which has in its central portion but somewhat out of line with the aperture 5, a pre-bored pin-hole 18 extending therethrough to further reduce the pressure of the gaseous fuel after passing through aperture 5. Then the cylindrical shell 19 of the valve mechanism is screwed into the boss 3 until a threaded plug 20 at the lower end of shell 19 seats against the disk 17. The plug 20 is shown as having annular ridges 21 on its lower end face which bite into the soft disk 17 to aid in forming a pressure-tight joint, and also the plug 20 is shown as having a central pressure reducing orifice 22 therein, through which the gaseous fuel passes. A valve cage 23 provided with an annular seat 24, is received within shell 19, and a valve member 25 is urged by spring 26 into engagement with seat 24 to shut off the flow of gaseous fuel from container 1. A further restricted orifice 27 may be provided, through which the gaseous fuel flows in entering the valve cage 23, after passing through the orifices 5, 18 and 22 previously described. When the valve member 25 is closed as above

described, a plunger 28 having a central stud 29 which rests against the valve member 25, is held in the relatively elevated position shown in Fig. 1, but when plunger 28 is depressed (by any suitable means not shown or described in detail) valve member 25 is pushed downwardly and unseated, whereupon gaseous fuel may flow out through the passageway 30 in plunger 29, the pressure at which the gas is thus delivered being reduced by passage through the restricted orifices above described. The plunger 28 may serve as the burner of the lighter, the gaseous fuel as it issues from passageway 30 being ignited by any appropriate means not specifically described or shown, whereupon the flame will continue as long as plunger 28 is held depressed and will be extinguished when this plunger is released.

When it is necessary to recharge the container with fuel, the valve mechanism will be removed, and the pressure reducing diaphragm is then deformed to release it from locking engagement with its seat. In Fig. 5 I have shown a type of tool 31 in the nature of a corkscrew which may be engaged with the wall of orifice 5 and drawn upwardly as indicated in Fig. 5 until the diaphragm member reassumes its initial shape, thus contracting its diameter and freeing it from its seat. The diaphragm member will then be removed, whereupon liquid fuel may be charged in through passageway 4, and a new diaphragm member inserted and the valve mechanism replaced, as above described.

While the invention has been disclosed as carried out by a diaphragm member of the above described specific construction, it should be understood that changes may be made therein without departing from the invention in its broader aspects, within the scope of the appended claims.

I claim:

1. In combination, a container for gas under pressure having a gas conducting passageway therein and a seat surrounding said passageway, a thin resilient metal diaphragm member mounted in said seat having in its central portion a pressure reducing aperture therethrough communicating with said passageway, said diaphragm having a natural somewhat concavo-convex curvature wherein its central portion surrounding said aperture is displaced to one side with respect to the general plane of the rim of the diaphragm and fitting within said seat when in such natural shape, but the central portion of said diaphragm being deformed to reverse its aforesaid natural curvature and expand the rim of the diaphragm into locking engagement in said seat, said diaphragm being deformable back to its natural curvature to release said engagement, and means engaging a face of said diaphragm to prevent reversal from its second mentioned curvature to its first mentioned curvature.

2. In combination, a container for gas under pressure having a gas conducting passageway therein and a seat surrounding said passageway, a thin resilient metal diaphragm member mounted in said seat having in its central portion a pressure reducing aperture therethrough communicating with said passageway, said diaphragm having a natural somewhat concavo-convex curvature wherein its central portion surrounding said aperture is displaced to one side with respect to the general plane of the rim of the diaphragm and fitting within said seat when in such natural shape, the aforesaid seat having an annular face disposed transversely to said passageway and against which the rim portion

of the diaphragm rests and an annular wall enclosing said diaphragm, the central portion of said diaphragm being deformed from its natural shape aforesaid to the opposite side of the plane of the rim of the diaphragm to reverse its natural curvature, and the rim of said diaphragm being pressed into locking engagement with said annular wall, and means engaging a face of said diaphragm to prevent reversal from its second mentioned curvature to its first mentioned curvature.

3. In combination, a container for gas under pressure having a gas conducting passageway therein and a seat surrounding said passageway, a thin resilient metal diaphragm member mounted in said seat having in its central portion a pressure reducing aperture therethrough communicating with said passageway, said diaphragm having a natural somewhat concavo-convex curvature wherein its central portion surrounding said aperture is displaced to one side with respect to the general plane of the rim of the diaphragm and fitting within said seat when in such natural shape, the aforesaid seat having an annular face disposed transversely to said passageway and against which the rim portion of the diaphragm rests and an annular wall en-

5 closing said diaphragm, the central portion of said diaphragm being deformed from its natural shape aforesaid toward the plane of the rim of the diaphragm, and the rim of said diaphragm being pressed into locking engagement with said annular wall, and a removable valve structure overlying the face of said diaphragm which is remote from the aforesaid transverse wall of the seat to clamp the rim of the diaphragm against said seat and hold said diaphragm in its aforesaid deformed shape.
